 The Orr Felt & Blanket Company, Piqua, Ohio,
 a corporation of Ohio

Application April 1, 1947, Serial No. 738,667

3 Claims. (Cl. 73—7)

1

The present invention relates to wear testing apparatus and is concerned primarily with a wear tester designed for use on paper making felts and comparable fabrics.

In providing testing apparatus of this type it is highly important that the actual conditions of usage be artificially reproduced to as great an extent as possible. This means the testing should be carried out under conditions closely simulating those in which the particular subject is used. When a paper making felt is employed tension is not constantly applied thereto. It is released at intermittent intervals. Thus, it is highly desirable in testing apparatus for such felts to reproduce this condition.

Accordingly, the invention has in view, as an important object, the provision of wear testing apparatus of the character indicated which includes means for placing a fabric under intermittent tension. Inasmuch as paper making felts are also subject to friction, the wear testing apparatus provided must also produce a comparable amount of friction.

A further object, therefore, lies in the provision of wear testing apparatus of the type aforesaid in which the frictional engagement is achieved under conditions of intermittent tension.

The main utility of a wear tester is to compare one piece of material to another. Thus, when one piece is tested it is important that the second piece be tested under identical conditions. In order to establish the frictional engagement it is necessary that the felt or other material be urged against the frictional elements under pressure. In the devices heretofore employed it has been difficult, if not impossible, to assure that this same pressure is exactly reproduced in different tests.

A further object, therefore, is the provision of wear testing apparatus including means for subjecting sheet material to friction while under intermittent tension and with an accurately predetermined pressure on the material.

In achieving these objects two knurled frictional rolls are employed in conjunction with a material carrying roll. All of these rolls are mounted for rotation at the same angular velocity. That is, they have the same number of revolutions per minute. The frictional effect is obtained by making the several rolls of different diameters so that their circumferential velocity varies.

The material carrying roll is so arranged with respect to the knurled rolls that the engagement of the material between one of the knurled rolls

and material carrying roll causes a tension in one direction while the corresponding engagement with the other knurled roll creates a tension in a reverse direction. This results in the alternate tensioning and release of the material.

A further somewhat more detailed object of the invention is the provision of new and improved means for urging the material carrying rolls against the knurled rolls. This end is attained by suspending the material carrying roll and associating with this suspension a weight which is effective to force the material carrying roll against the knurled rolls under gravity action.

More in detail, a further object is the provision of apparatus of the character aforesaid in which the pressure on the material carrying roll may be varied as occasion demands. This is achieved by making the weight, which urges the material carrying roll against the knurled rolls, adjustable.

20 A further object lies in the provision of a wear testing apparatus of the type above indicated which is susceptible of carrying out testing operations on paper making felts and similar material under either wet or dry conditions. In attaining this end a pan is positioned immediately beneath the material carrying roll and this pan is adapted to receive water, or other solution to which a paper making felt is likely to be subjected during actual service usage. The material carrying roll extends into the pan and as it is rotated, the material carried thereby is wetted.

Various other and more detailed objects and advantages such as arise in connection with carrying out the above noted ideas in a practical embodiment will in part become apparent and in part be hereinafter stated as the description of the invention proceeds.

The invention, therefore, comprises wear testing apparatus including means for subjecting sheet material to an accurately predetermined friction under conditions of alternating tension and release of the material.

For a full and more complete understanding of the invention, reference may be had to the following description and accompanying drawings wherein:

Figure 1 is a perspective view of wear testing apparatus designed in accordance with the precepts of this invention;

50 Figure 2 is an enlarged perspective view with the cover removed and certain parts broken away and shown in section;

Figure 3 is a longitudinal section taken about on the planes represented by the lines 3—3 of Figure 1; and

Figure 4 is a detailed showing of the rolls per se taken on a plane normal to the axis of the rolls. This view is taken about on the plane represented by the line 4—4 of Figure 2.

Referring now to the drawing wherein like reference characters denote corresponding parts, the wear testing apparatus provided by this invention may be mounted within a casing comprising a bottom 10, end walls 11 and 12, and a rear wall 13 which is curved at its top to provide a protecting canopy 14. Upstanding from the base 10 are a pair of vertical supports 15 and 16. These supports 15 and 16 are provided with openings in which certain shafts are journaled as will be hereinafter pointed out. They also are provided with slots 17 extending upwardly from the bottom and on their outer faces carry plates 18 which are formed with slots in alignment with the slots 17.

A pair of shafts 19 are journaled in openings formed by the supports 15 and 16 and are in alignment. Between the latter elements the shafts 19 carry a knurled roll 20 which is divided into sections by the annular grooves 21. In the illustrated embodiment of the invention the roll is shown as divided into six sections. Obviously this can be varied and is not a limitation of the invention. At each end the shafts 19 carry a gear 22 that is drivably mounted on the shaft between the respective support and end wall.

Another pair of shafts 23 are also journaled between the supports 15 and 16 and have their ends projecting therebeyond. Between the members 15 and 16 the shafts 23 carry a knurled roll 24 which is divided into sections corresponding in number and arrangement to the sections of the knurled roll 20. The purpose of providing these sections is to accommodate the testing of different fabrics simultaneously. At each end spaced between the respective support and end wall the shafts 23 have drivably mounted thereon a gear 25.

Slidably positioned in each of the slots 17 is a shaft 26. Between the members 15 and 16 the shafts 26 drivably carry a material carrying roll 27. Upon referring to Figure 4 it will be noted that this roll 27 is formed with a groove 28 extending lengthwise thereof. The material to be tested is shown at 29. Each piece of material is anchored in position on the roll 27 through the medium of a block 30 which clamps the ends of the material against the walls of the groove 28 and the block 30 is held in this position by the screw shown at 31. Each of the shafts 26 carry, adjacent to its free end, a pinion 34 which is drivably mounted thereon.

The material carrying roll 27 extends down into a pan 32 which may be supported in position by the bolt and nut arrangement shown at 33. When the material 29 is to be tested wet, the pan 32 is filled with water, or other fluid to which a paper making felt is subjected during usage, whereby the material is wetted. There are times during a paper making operation when solutions having various degrees of acidity or alkalinity are employed. The felts are subject to these solutions and if service conditions are to be accurately reproduced in the testing apparatus, provision must be made for immersing the materials in such solutions. This is accommodated by the pan 32. Brackets shown at 35 are carried on the inner faces of the members 15 and 16 and cooperate with the bolts 33 in positioning the pan 32.

Extending through the aligned slots of the plate 18 and the respective support is a shaft member

36. Between the members 15 and 16 the shafts 36 carry a weight 37 which may take the form of the roll illustrated. Outside the respective supports 15 and 16 each of the shafts 36 carries a gear 38 and the shaft is continued therebeyond to provide a shaft section 39 that is adapted to receive removable weight members 40. The latter is held in position by the nut shown at 41.

An endless chain 42 passes over the gears 22 10 and 25 and beneath the pinion 34 so as to hold the material carrying roll in a suspended position. Likewise, the chain 42 passes beneath the gears 38 and suspends the weights 37 and 40 in such a manner that they urge the material carrying roll 27 upwardly against the knurled rolls 20 and 24.

Each of the shafts 19, 23, and 26 are driven at the same number of revolutions per minute. Thus, the angular velocity is uniform. However, 20 as illustrated in the drawings, the knurled roll 20 is of one diameter, the roll 24 of another, and the roll 27 of still another. Thus, each of these rolls has a different circumferential velocity. Moreover, it will be noted from Figure 25 4, that, due to the arrangement of the rolls, the material is tensioned in one direction by the engagement between the rolls 20 and 27 and in the opposite direction by the engagement between the rolls 24 and 27. The engagement between 30 the rolls 20 and 27 is depicted at the point *a* while that between the rolls 24 and 27 is shown at *b*. Between the points *a* and *b* the material 29 is released.

The several rolls may be driven in any preferred manner. As shown in the drawing, the end wall 12 may be formed with an opening 43 through which the shaft 19 is extended. Any appropriate power source may be availed of to drive the shaft 19.

Operation

In using the above described apparatus specimens of the material to be tested will be anchored to the roll 27 in the manner depicted. A record 45 will be kept of the total weight of the roll 37 and weights 40 as these determine the pressure under which the roll 27 is urged against the knurled rolls. The shaft 19 will be driven at a predetermined rate of speed and the material is tested a prescribed period of time.

50 If the material is to be tested dry, the pan 32 may be removed or left dry; while if it is to be tested wet, this pan will be filled with water, or any other solution to which paper making felt might be subjected. After the tests have 55 been completed, the specimens may be examined and it will be known just how much they will act under certain conditions, all of which may be accurately recorded. It is then possible to submit other specimens to the tests under conditions 60 which will accurately duplicate those of the first test. Thus, the apparatus provided hereby is peculiarly adapted for the testing of materials and keeping an accurate record of the conditions under which they were tested.

65 While a preferred specific embodiment of the invention is hereinbefore set forth, it is to be clearly understood that the invention is not to be limited to the exact constructions illustrated and described because various modifications of 70 these details may be provided in putting the invention into practice within the purview of the appended claims.

What is claimed is:

1. In wear testing apparatus, a friction roll 75 having a gear at each end, a second friction

roll of a diameter different from said first friction roll and having a gear at each end, a material carrying roll adapted to engage said friction rolls and having a diameter different from that of either of said friction rolls, a pinion at each end of said material carrying roll, a pair of endless chains, one being arranged at each end of said rolls so that it passes over said gears and beneath said pinion to suspend said material carrying roll, a gear engaging each of said chains within the lower bends thereof, and an adjustable weight carried by said gears.

2. Apparatus of the character described comprising a base, supporting members upstanding from said base in spaced relation, a shaft journaled in said supports and carrying therebetween a friction roll, a second shaft journaled in said supports and carrying therebetween a second friction roll of a diameter different from said first friction roll, said supporting members being formed with slots beneath the bearings of said shafts, shaft means in said slots and carrying between said supporting members a material carrying roll, suspension means for said shaft means, means cooperating with said suspension means for urging said material carrying roll against said friction rolls under gravity action, and a water pan carried by said supporting members beneath said material carrying roll into which said material carrying roll is adapted to 30 project.

3. Apparatus of the character described comprising a base, supporting members upstanding from said base in spaced relation, a friction roll positioned between said supports and including 5 shaft means journaled therein, a second friction roll of a diameter different from said first friction roll and including shaft means journaled in said supports, said supporting members being formed with slots beneath the bearings of said 10 shafts, shaft means in said slots and carrying between said supporting members a material carrying roll, suspension means for said shaft means, means cooperating with said suspension means for urging said material carrying roll against said friction rolls under gravity action, and a pan disposed beneath said material carrying roll is adapted to project, said pan being adapted to 15 receive a solution to which a paper making felt 20 is subjected during actual use.
